Primary Examiner — Holly Baynham*Assistant Examiner* — Rashida C Walshon(74) *Attorney, Agent, or Firm* — Belles Katz LLC(57) **CLAIM**

I claim the ornamental design for a swimsuit, as shown and described.

DESCRIPTION

FIG. 1 is a front view of a swimsuit on a model showing my new design.

FIG. 2 is a rear view of the swimsuit of FIG. 1.

FIG. 3 is a right-side view of the swimsuit of FIG. 1; and, FIG. 4 is a left-side view of the swimsuit of FIG. 1. The broken lines formed by linear segments of equal length are provided for environment only and form no part of the claimed design.

1 Claim, 4 Drawing Sheets(56)
